(57) CLAIM

The ornamental design for an applique and quilting pattern design applied to bags, as shown and described.

DESCRIPTION

FIG. 1 is a perspective view of a first embodiment of the applique and quilting pattern design applied to bags of my new design from the front, left;

FIG. 2 is an elevational view thereof from the front, shown in the fastened configuration;

FIG. 3 is an elevational view thereof from the left;

FIG. 4 is an elevational view thereof from the right;

FIG. 5 is a perspective view of a second embodiment of the applique and quilting pattern design applied to bags of my new design from the front, left;

FIG. 6 is an elevational view thereof from the front;

FIG. 7 is an elevational view thereof from the left;

FIG. 8 is an elevational view thereof from the right;

FIG. 9 is a perspective view of a third embodiment of the applique and quilting pattern design applied to bags of my new design from the front, left;

FIG. 10 is an elevational view thereof from the front;

FIG. 11 is an elevational view thereof from the left; and,
FIG. 12 is an elevational view thereof from the right.

The rear and bottom views of all the foregoing embodiments are flat and devoid of surface ornamentation.

The top views of all the foregoing embodiments are sufficiently shown in the perspective views and devoid of surface ornamentation.

The dashed lines in FIGS. 1-12 show stitching which is part of the claimed design.

The dotted lines in FIGS. 1-12 show unclaimed environmental structure and portions of the bags that form no part of the design.

The lightly drawn unbroken lines in the lower right, diagonal portions of FIGS. 1-12 show shading from a light source at a forty-five degree angle from the upper left to lower right.
